UNITED STATES PATENT OFFICE.

GEORGE F. ROOKE, OF PROVIDENCE, RHODE ISLAND.

DESIGN FOR A TOY BANK.

Application filed February 10, 1922. Serial No. 634. Term of patent 14 years.

To all whom it may concern:

Be it known that I, GEORGE F. ROOKE, a citizen of the United States, residing at Providence, in the county of Providence and State of Rhode Island, have invented a new, original, and ornamental Design for a Toy Bank, of which the following is a specification, reference being had to the accompanying drawing, forming part thereof.

Of the drawing,—

Figure 1 is a plan view of a toy bank containing my new design.

Figure 2 is a front elevation of the same.

Figure 3 is a right hand elevation.

Figure 4 is a perspective view.

I claim:

The ornamental design for a toy bank, as shown.

GEORGE F. ROOKE.
